UNITED STATES PATENT OFFICE.

FRANCIS J. HEALEY AND SIDNEY ROWLAND SHEPPARD, OF SOUTHALL, ENGLAND.

VULCANIZING-MACHINE.

1,196,109.

Specification of Letters Patent. Patented Aug. 29, 1916.

Application filed June 28, 1915. Serial No. 36,852.

To all whom it may concern:

Be it known that we, FRANCIS JEREMIAH HEALEY and SIDNEY ROWLAND SHEPPARD, subjects of the King of England, residing at 5 Southall, in the county of Middlesex, England, have invented certain new and useful Improvements in Vulcanizing-Machines; and we do hereby declare the following to be a full, clear, and exact description of the invention, such as will enable others skilled in the art to which it appertains to make and use the same:

This invention relates to vulcanizing apparatus and more particularly for use in vulcanizing continuous sheets or webs by a continuous process.

An object of this invention is to provide an improved and simplified form of machine through which a continuous web of material 20 may be passed and vulcanized.

A further object of this invention is to provide a means for mounting a series of rollers to receive a web of material therebetween with adjusting means for some of said 25 rollers to regulate the bearing relation against the web passing between said rollers.

A further object of this invention is a provision for means for applying lacquer or any other material to said web before it is 30 passed through the treating processes.

A further object of this invention is the provision of a powdering apparatus for applying powder to the web during its treatment.

35 Further objects will be apparent from the following specification, appended claims and drawings in which—

Figure 1 is a side elevation of the machine showing the arrangements of the rollers, 40 Fig. 2 is a similar view thereof showing one mode for driving said rollers and Fig. 3 is a sectional view as on the line 3—3 of Fig. 1, showing parts in elevation.

This invention enables a continuous web of 45 rubber or similar material being vulcanized by a continuous process and comprises a series of rollers which may be heated to the desired degree to receive the web of material therebetween, together with means for applying 50 a lacquer or similar treatment before passing between the several rollers and means for applying powder to the web before the completion of its treatment.

Referring to the drawings in which similar 55 reference numerals indicate similar parts there is shown a base 49 upon which the

frames 50 are mounted as well as the frame 51 in which rollers 52 and 53 are journaled. The roller 53 is supported at each end by a sliding bearing 54 which may be moved by 60 the screw 55 to which the handwheel 56 is secured. The roller 52 is journaled at each end in a stationary bearing 57 and this roller co-operates with the downwardly tapering wall 58 forming a chamber 59 in which a 65 lacquer common to the rubber trade for enameled purposes or other material may be placed. A doctor 60 supported by the lower edge of the wall 58 bears against the roller 52 and through the manipulation of the 70 thumb screw 61 regulates the passage of the liquid through the interstice between said doctor and said roller.

The frames 50 may be made uniformly 75 and interchangeable and when assembled as shown, these frames support frames 62 in which drums 63 are journaled as in the fixed bearing 64. The frames 50 support drums 65 in movable bearings upon the screws 67 to which the handwheels 68 are secured. A 80 roller 69 is mounted in a frame 70 which may be attached to one of the frames 50 and this roller receives the web as it passes from the rollers 52 and 53 and feeds said web to the roller 65 in proximity thereto. The web 85 then passes between the first roller 65 and a roller 71 journaled as at 72 in the fixed bearings of the frame 73 from where said web is fed continuously between the drums 63 and 65.

90 Before completing the treatment of the web, it passes under a powder apparatus comprising the roller 74 which has a portion of its circumference disposed within the powder receptacle 75 so that as said 95 roller is rotated it continuously feeds a limited supply of powder such as talc or French chalk to the web. This roller may be of a brush formation if so desired.

One of the trunnions for each of the 100 drums 63 and 65 has a gear 76 secured thereto and these gears are of such proportions as to mesh with one another so that power applied to one of said gears correspondingly drives the others. The other of 105 the trunnions for the drums 63 and 65 is of hollow formation to receive the pipes 77 and 78 which terminate at a fitting 79 to which the steam supply pipe 80 and the exhaust pipe 81 are connected. The pipe 77 110 conducts the live steam to the interior of the drums and the pipe 78 discharges the

- condensate therefrom as through the depending elbow 82 to the exhaust pipe 81. The escape of steam between the hollow trunnion and the pipe 78 is checked by the 5 packing 83 held in place by the gland 84. The several pipes 80 will be connected by flexible connections to a common source and in like manner the exhaust pipes 81 will be connected to a common exhaust outlet.
- 10 It is apparent that by the use of a machine of this character, a web may be fed continuously through the machine and treated on its passage therethrough. If so desired, the drum 63 and the drum 65 may 15 each be enveloped by endless tapes shown in dotted lines, to direct the passage of the web between the rollers.
- Further description of this device is thought unnecessary as it is clearly seen 20 how the drums 63 and 65 could be heated to the desired temperature and how the several drums may be adjusted to produce the desired bearing relation upon one another and how the several drums may be 25 driven on the desired speed. It is further understood that modifications may be made without departing from the spirit of the invention as the drawings are submitted for illustrative purposes only.
- 30 Having thus described our invention, we claim:—
1. A machine for vulcanizing a continuous webbing comprising a plurality of driven and heated drums, some of said 35 drums being supported in adjustable bearings, a roller in advance of said drums to apply a lacquer to said webbing preparatory to its passage between the heated drums and means whereby the thickness of 40 the film of lacquer may be regulated.
  2. A machine for vulcanizing a continuous webbing, comprising a plurality of driven and heated drums to receive a continuous webbing therebetween, a roller for 45 applying a film of lacquer to said webbing preparatory to its passage between said
- drums, and a powdering device disposed between some of said rollers for applying a powder to said webbing in its treatment between said drums. 50
3. A machine for vulcanizing a continuous webbing comprising a frame, a plurality of drums journaled in fixed bearings, a plurality of corresponding drums journaled in movable bearings, each of said 55 drums being disposed to establish an impinging action on the two adjacent drums in the opposite row of drums, said drums being relatively adjustable to vary the thickness of an inserted web therebetween, 60 a roller for applying lacquer to a web before passing through said drums and a powdering device for applying powder to an inserted web during the treatment of the web in said drums. 65
4. A machine for vulcanizing a continuous webbing comprising a frame, a plurality of driven and heated rollers journaled in said frame in fixed bearings, a plurality of driven and heated drums journaled in said frame in movable bearings, said second mentioned drums being in staggered relation to said first mentioned drums, said frames being disposed to have their peripheries contact with and bind 70 against a webbing passing between said drums, a lacquering roller carried by said frame in advance of said heated drums, means for varying the thickness of a film 75 of lacquer applied to a web passing under said roller and a powdering device carried by said frame between some of said heated drums disposed to supply a powder to a web passing between said heated drums in the treatment of said web. 80
